SCRAPER BLADE

Ted L. Cline, P.O. Box 38, Rush Springs, Okla. 73802

Filed Jan. 9, 1969, Ser. No. 15,282

Term of patent 14 years

Int. Cl. D12—14

U.S. Cl. D14—3

— E — I — E — I —

— E — I — E — Z —

FIGURE 1 is a perspective view of a scraper blade incorporating my new design.

FIGURE 2 is a rear elevational view of the scraper blade depicted in FIGURE 1.

FIGURE 3 is a side elevational view of the scraper blade depicted in FIGURE 1.

FIGURE 4 is a top plan view of the scraper blade depicted in FIGURE 1.

FIGURE 5 is a bottom plan view of the scraper blade depicted in FIGURE 1.

I claim:

The ornamental design for a scraper blade, substantially as shown.
